US00D992286S

(12) **United States Design Patent** (10) **Patent No.:** **US D992,286 S**
(45) **Date of Patent:** **** Jul. 18, 2023**

(54) **BRUSH FERRULE**

(71) Applicant: **Anisa International, Inc.**, Atlanta, GA (US)

(72) Inventors: **Sarah Soto**, Atlanta, GA (US); **Shuai Chen**, Atlanta, GA (US)

(73) Assignee: **Anisa International, Inc.**, Atlanta, GA (US)

(**) Term: **15 Years**

(21) Appl. No.: **29/852,847**

(22) Filed: **Sep. 9, 2022**

Related U.S. Application Data

(63) Continuation of application No. 29/690,766, filed on May 10, 2019, now Pat. No. Des. 968,818.

FIG. 1 is a bottom perspective view of an aspect of a brush ferrule.

FIG. 2 is a front elevation view thereof.

FIG. 3 is a rear elevation view thereof.

FIG. 4 is a right-side elevation view thereof.

FIG. 5 is a left-side elevation view thereof.

FIG. 6 is a top plan view thereof; and,

FIG. 7 is a bottom plan view thereof.

Those features shown in broken lines form no part of the claimed design.
